FIG. 1

FIG. 2

FIG.3

FIG.4

FIG.5

FIG.6

FIGURE 1 is a side elevation view of a portable lantern, showing my new design;

FIGURE 2 is a top plan view thereof;

FIGURE 3 is a front elevational view thereof;

FIGURE 4 is a fragmentary, enlarged, cross-sectional view taken along the line 4-4 of FIGURE 3;

FIGURE 5 is a rear elevational view thereof; and

FIGURE 6 is a fragmentary, enlarged, detailed view of the bottom of the lantern showing a typical corner and a typical front, rear, and side edges of the bottom.

The dominant features of the design reside in the portions shown in full lines.

The undisclosed side of the lantern is substantially the same as the side shown in FIGURE 1.

I claim:

The ornamental design for a portable lantern, as shown and described.
